CLAIM

The ornamental design for a beverage container with lid, as shown and described.

DESCRIPTION

FIG. 1 is a top front isometric view of a beverage container with lid showing our new design;

FIG. 2 is front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a bottom rear isometric view thereof.

The dashed lines in the drawings illustrate portions of the beverage container with lid that form no part of the claimed design.
